TELEPHONE SYSTEM

Alfred Wiessner, Berlin-Charlottenburg, Germany, assignor to Siemens & Halske Aktiengesellschaft of Wernerwerk, of Siemensstadt near Berlin, Germany

Application February 19, 1932, Serial No. 594,065,
and in Germany March 12, 1931

9 Claims. (Cl. 179—16)

This invention relates to a circuit arrangement for initiating switching operations over inductively connected lines in telephone systems.

It solves the problem of causing various switching operations to be performed at the incoming end of a line in consequence of the various manners in which switching means at the outgoing end of said line have been actuated.

This is achieved by switching means for transmitting induced impulses being arranged at the outgoing end of the line, said switching means causing an impulse receiving relay at the incoming end of the line to be momentarily energized when a switch is thrown over and permanently energized upon said switch being restored to its original position.

An embodiment of the invention is shown in the drawings, said embodiment illustrating the use of the invention in automatic telephone systems and showing the simple manner in which the device according to the invention seizes and releases various connecting devices. The reference letters TSt in Fig. 1 represent a subscriber's station inductively connected to the one end of the subscriber's line TL, and Ue a repeater connected in the same way to the other end of the line TL. Fig. 2 shows the succeeding preselector VW and group selector GW.

The arrangement operates in the following manner:

When the subscriber at the station TSt lifts his receiver, the switch hook Hs is closed and a circuit for relay S is set up over said switch hook. Relay S is energized and closes contact 1s which results in a circuit being closed over: earth, battery, contacts 3v1, 1s, winding I of the transformer Tr, earth. Contact 2s also is closed and consequently relay V1 is connected up upon the energization of relay S. Relay V1, when energized, throws contact 3v1 over into position 4v1 with the result that the circuit set up by the closing of contact 1s is again cut off. Contact 5s being opened no current is able to flow over contact 4v1.

The closing of the switch hook Hs therefore sets up the circuit which extends over winding I of the transformer Tr momentarily only. An impulse therefore, is induced in winding III of the transformer at the closing of this circuit as well as at the opening of said circuit. These two induced impulses reach the speaking current repeater Sp I and thence over the line TL the repeater SP2 from which they are repeated to the impulse receiving relay P1 over contacts 6h and 7h. The last mentioned relay is constructed as a polarized relay having a neutral normal position and is actuated by the received impulses in such a man-

ner that its armature is thrown over in a position corresponding to the direction of the impulses.

The first impulse, that is to say, the impulse produced on the closing of contact 1s influences relay P1 in such a manner that it throws over its armature, thus closing contact 8p1, whereas the second impulse, that is to say, the impulse produced by the opening of contact 3v1 influences relay P in the opposite direction causing it to restore its armature to normal. Relay J is energized over contact 8p1 and closes contact 9j and also connects up relay D over earth, contact 9j, relay D, resistance W1, battery, earth. Relay D closes its contacts 10d, 11d, 12d, 13d and 14d and opens contact 15d. Contact 14d sets up a locking circuit for said relay, and the succeeding preselector VW is seized over contact 10d, a circuit for relay R2 being closed over: earth, battery, resistance W2, contacts 10d, 26e, b'-lead, relay R2, earth.

Relay R2 in the preselector VW in Fig. 2, therefore, is energized and closes contacts 16r2 and 17r2. This sets up a circuit for the rotary magnet over: earth, battery, contacts 16r2, 18t, rotary magnet D, interrupter U and causes the circuit of the magnet D to be intermittently closed and opened with the result that the switch wipers of the preselector are advanced until an idle succeeding group selector has been reached.

When this occurs relays T and C are energized over: earth, battery, contacts 17r2, relay T, c-wiper of the preselector, c-lead, off-normal contact 22k, winding I of relay C, earth. Relay T puts its contact 18t into position 19t and thus disconnects the rotary magnet D which in turn brings the preselector to rest. In addition, it closes its contacts 20t and 21t, thus switching through the speaking leads to the group selector. Contacts 23c and 27c are closed when relay C is energized. Due to the switching through of the speaking leads, relay R1 in the repeater Ue is energized in series with relays A and B in the group selector GW. Relay R1 closes its contacts 32r1 and consequently causes relay E to be energized. This relay closes its contacts 33e and 34e and opens contact 26e. In addition, contact 43r1 is opened by relay R1. Relay A places its contact 24a in the position 25a with the result that relay V1 is energized over: earth, battery, contact 23c, winding II of relay C, contact 25a, relay V3, earth. Relay V3 opens contact 28r3 and closes contact 29v3. This prepares the seizure of the succeeding but not shown final selector.

When, for the purpose of setting the switch,

the subscriber operates his dial, contact 30n in Fig. 1 is intermittently closed which sets up a circuit over: earth, battery, contact 30n, winding I of the transformer Tr, earth. The induced currents generated by the closing of this circuit in winding III of the transformer are transmitted in the manner described above to the impulse receiving relay P1, which upon receiving these impulses connects up relay J by means of its contact 8p1 and thus causes the impulses to be transmitted to relay A of the group selector over contact 31j. This relay actuates the not shown vertical magnet of the group selector and causes the switch wipers of said group selector to be raised to the required level and later to hunt for an idle final selector at the end of the impulse series in the usual manner. The further setting up of the connection to the required subscriber takes place in known manner and is not described in detail since this is not necessary for the understanding of the invention. Relay V4 is energized at the commencement of the impulse series for the setting of the final selector due to the closing of contact 24a, remains energized during the complete impulse series and by means of contact 53v4 applies control potential to the outgoing b-lead. Relay P2 also is energized and closes its contacts 35p2, 36p2 and 37p2.

When, at the end of the conversation, the called subscriber replaces his receiver, potential will be applied to the b-lead in the not shown final selector, thus causing relay B1 to be energized over: earth, relay B1, contact 27c, winding of the speaking current repeater Sp3, contacts 38v4, 36p2, b-wiper of the group selector, b-lead, battery applied to this lead in the final selector, earth. Relay B1 closes contacts 39b1, thus releasing relay C due to its winding I being disconnected by the opening of the off normal contact 22k at the first vertical step of the switch. Relay C opens contact 23c which causes relay V1 also to be released. This opens contact 29v3 so that relay P2 releases. Consequently contact 40p2 is closed and sets up a circuit for the release magnet M over: earth, applied to the off normal contact 41k which is closed at the first vertical step, contacts 40p2, 28v3, magnet M, battery, earth. Magnet M restores the group selector to normal in known manner. The magnet, in addition, opens its contact 42m which breaks the c-lead to the preselector and causes relay T to release. Contacts 20t and 21t are consequently opened and contact 18t closed.

It will now be assumed that the calling subscriber has not yet replaced his receiver. Due to the opening of contacts 20t and 21t, relay R1 in the repeater Ue is caused to release with the result that contact 43r1 is closed and contact 32r1 is opened. Relay H will, therefore, be connected up over: earth, contacts 43r1, 34e, relay H, battery, earth. Relay H closes contact 44h which causes relay D to release. This, in turn, opens contact 10d and cuts off battery from the b-lead. This disconnection takes place before relay E has closed its contact 26e as relay E releases with very slow action upon the opening of contact 18d. This prevents the preselector Vw from operating afresh if the calling subscriber should not have replaced his receiver at the time the called subscriber has hung up.

If, on the other hand, the calling subscriber hangs up his receiver first the circuit for relay S is cut off by the opening of the switch hook Hs so that contacts 1s and 2s are opened and con-

tact 5s is closed. The opening of contact 1s has no effect since contact 4v1 now is closed. The closing of contact 5s, on the other hand, sets up a circuit over: earth, battery, contacts 4v1, 5s, winding II of the transformer Tr, earth, which circuit is again cut off upon the release of relay V1 due to the opening of contact 2s so that contact 4v1 is thrown into position 3v1. The induced impulse generated at the setting up of the above circuit travels in the opposite direction to the impulse produced in winding III of the transformer on the closing of contact 1s in the manner described above. Therefore, it has no effect on relay P1. Only the induced impulse produced on the opening of contact 4v1 affects relay P1 causing said relay to actuate its armature and retain it in its operative position until it is restored to normal in the manner to be more explicitly described below.

Relay P1, thus, has closed contact 8p1 and thereby connected up relay J. Due to this operation contacts 45j, 46j and 47j are closed. A circuit for relay V2 is set up over: earth, contacts 12d, 45j, relay V2, resistance W3, battery, earth, as contact 12d is closed. Relay V2 closes contacts 49v2 and 50v2. This produces a short circuit for relay D over contacts 46j and 50v2, which causes relay D to release and disconnect battery from the b-lead to the preselector by means of contact 10d. Contact 15d also is closed upon the release of relay D so that relay H is connected up over: earth, contacts 47j, 15d, relay H, battery, earth. This relay is energized and closes its contacts 51h and 52h and thus completes a circuit for relay P1 in which the current extends in such a direction that the relay restores its armature to normal and consequently re-opens contact 8p1. Contact 48j is closed on the release of relay J, causing relay V2 to release due to the short circuit produced thereby. The contact 11d being opened upon the release of relay D, relay R1 also releases with the result that all the switching means associated with the repeater are restored to normal.

The succeeding connecting devices are then released in the manner described above by the called subscriber replacing his receiver.

The invention is not limited to the embodiment described. The switching means for the initiation of the switching operations may be arranged at an operator's position instead of in a subscriber's station.

What is claimed is:

1. In a telephone system, an inductively connected subscriber's line, an impulse receiving device at the incoming end of said line, a transformer at the outgoing end of said line, means responsive to the removal of the receiver by a calling subscriber for closing and opening a circuit including the primary winding of said transformer, said device operated responsive to the induced current generated by the closure of said circuit and restored to normal responsive to the induced current generated by the opening of said circuit, and means responsive when the calling subscriber replaces the receiver for momentarily closing the circuit including the primary winding and for altering the same so that the device will operate only responsive to the induced current generated by the opening of said circuit.

2. In a telephone system, an inductively connected subscriber's line, an impulse receiving device at the incoming end of said line, a transformer at the outgoing end of said line, means

- responsive to the removal of the receiver by a calling subscriber for closing and opening a circuit including the primary winding of said transformer, said device operated responsive to the induced current generated by the closure of said circuit and restored to normal responsive to the induced current generated by the opening of said circuit, means responsive when the calling subscriber replaces the receiver for momentarily closing the circuit including the primary winding and for altering the same so that the device will operate only responsive to the induced current generated by the opening of said circuit, and means controlled by said device for subsequently restoring said device to normal. 5
3. In an automatic telephone system, a subscriber's line terminating in a repeater, a transformer at the subscriber's end of said line having its secondary winding bridged across the line conductors, a polarized relay in the repeater, a two-section primary winding for said transformer, means responsive to the removal of the receiver by a calling subscriber for momentarily completing a circuit including the first section of the primary winding to induce current in the secondary winding, the induced current generated by the closing of the primary circuit being of the direction to operate the polarized relay and the current generated by the opening of the circuit 20 being of the reverse direction to restore the relay to normal, means in said repeater responsive to the momentary operation of said relay for extending said line to an automatic switch, a second circuit including the first section of the primary winding momentarily completed to transmit induced impulses to operate said relay when the subscriber dials, means controlled by said relay for repeating the impulses to set the automatic switch, means responsive when the calling subscriber hangs up his receiver for momentarily completing a circuit including the second section of the primary winding, the induced current generated by the closing of this circuit being of the reverse direction required for operating the relay 25 and the induced current generated by the opening of this circuit being in the proper direction for operating the relay, and means responsive when the relay remains in its operated position for releasing the automatic switch and for energizing the relay to restore the same to normal to release the repeater. 30
4. In an automatic telephone system, a subscriber's line terminating in a repeater, a lineswitch individual to said repeater for extending said line to an automatic switch, a transformer at the subscriber's end of said line, means responsive to the removal of the receiver by a calling subscriber for momentarily closing a circuit including the primary winding of said transformer to transmit induced impulses over said line, a polarized relay in said repeater operated responsive to the induced current generated by the closing of said circuit and restored to normal responsive to the induced current generated by the opening of said circuit, means responsive to the momentary operation of said relay for operating said lineswitch to extend said line to an automatic switch, means for operating said polarized relay to repeat impulses dialled by said subscriber to set the automatic switch, means responsive when the calling subscriber hangs up for momentarily closing the primary circuit and for altering 35
- the same so that the polarized relay will not operate responsive to the induced current transmitted when the circuit is closed and will operate when the circuit is opened, and means responsive when said relay remains in its operated position for releasing said lineswitch and automatic switch and for energizing said relay to restore it to normal to release the repeater. 40
5. In an automatic telephone system, a calling subscriber, a switch in an exchange, means at the subscriber's station for transmitting impulses, a polarized relay in said switch momentarily operated by each of the impulses transmitted to set said switch to establish a connection, means at the subscriber's station for transmitting an impulse when the subscriber hangs up, said relay adapted to remain in its operated position responsive to the impulse transmitted when the subscriber hangs up, and means in said switch operated when said relay remains in its operated position for releasing said switch and said relay. 45
6. In an automatic telephone system, means at a subscriber's station for making and breaking a circuit including a winding of a transformer to transmit induced impulses, a relay in an automatic switch adapted to be energized by the induced current generated on the make of said circuit and restored to normal by the induced current generated on the break of said circuit to set said switch to complete a connection, means for altering said circuit and for momentarily closing the same when said subscriber hangs up, said relay adapted not to energize responsive to the induced current generated on the make of the altered circuit and to energize and remain in its energized position responsive to the induced current generated on the break, and means operated when said relay remains in its energized position for releasing said switch and for completing a circuit for releasing said relay. 50
7. In combination, a telephone line, a transformer having the secondary winding connected to said line, means responsive to the removal of the receiver for automatically closing and opening a circuit through the primary winding, thereby inducing two impulses in the secondary winding, and means responsive to the replacement of the receiver for automatically closing and opening a reversed circuit through the primary winding, thereby inducing two impulses in the secondary winding which are of opposite polarity, respectively, as regards to said first two induced impulses. 55
8. In combination, a telephone line, a telephone instrument, means responsive to the removal of the receiver and also to the replacement thereof for automatically transmitting two impulses of opposite polarity over said line, and means for automatically reversing the order in which the second pair of impulses are transmitted. 60
9. A telephone system which includes a telephone instrument and line as set forth in claim 8, which is further characterized by the provision of a polarized relay and an automatic switch at the exchange, said relay being responsive to a pair of impulses received in normal order to operate said switch and responsive to a pair of impulses received in reverse order to release said switch. 65
